UNITED STATES PATENT OFFICE.

LEWIS S. BROWN, OF COLUMBUS, OHIO.

COIN-CONTROLLED BICYCLE-PUMP.

SPECIFICATION forming part of Letters Patent No. 626,268, dated June 6, 1899.

Application filed September 21, 1898. Serial No. 691,492. (No model.)

To all whom it may concern:

Be it known that I, LEWIS S. BROWN, of Columbus, in the county of Franklin and State of Ohio, have invented a new and Improved 5 Coin-Controlled Bicycle-Pump, of which the following is a full, clear, and exact description.

My invention relates to an improvement in the mechanism of coin-controlled bicycle-pumps, and comprises the novel features hereinafter described and claimed.

Reference is to be had to the accompanying drawings, forming a part of this specification, in which similar characters of reference indicate corresponding parts in all the figures.

15 Figure 1 is a side elevation of my device. Fig. 2 is an elevation taken at right angles to Fig. 1. Fig. 3 is a section taken through a portion of the casing, showing the means used for locking the crank-shaft. Fig. 4 is a sectional elevation of the lower portion of the casing, other parts being shown connected therewith. Fig. 5 is a similar view showing the parts in a different position. Fig. 6 is a partly-sectional elevation of details, taken 20 upon the line 6 6 of Fig. 4; and Fig. 7 is a similar section taken on the line 7 7 of Fig. 5 and showing the same parts in different position.

The object of my device is to provide means by which a mechanism for inflating a bicycle 30 or other pneumatic tire may be released by the insertion of a coin, and thus permit the tire to be inflated. It comprises a pump which normally is locked, so that it cannot be operated, and means by which the pump-operating 35 means may be released by the insertion of a coin.

The operating and controlling mechanism of my device is included within a casing A, which is of any suitable form. Journaled in 40 this casing at a convenient height for rotation is a shaft B, which has upon one end a fly-wheel B', provided with a crank by which it may be turned, and upon the other end a crank-disk B². Upon the base of the casing 45 is mounted a pump D, which is of any suitable form and has the pump piston-rod C extending upward along one face of the casing and sliding within guide a. This pump piston-rod is connected with the crank-disk by 50 means of a rod C', which at its upper end is pivoted to the rod C and at its lower end is pivoted upon a crank-pin b, carried by the

crank-disk B². The crank-disk B² occupies an opening in one face of the casing and has a series of pins b' projecting from its inner 55 face. Mounted upon the casing beneath the disk B² is a locking-lever F, which is pivoted so that its upper end may be inserted between adjacent pins b' upon the disk, and thus lock it against rotation. This is the normal position of the locking bar or lever F.

Pivoted upon a shaft E', which is journaled in the casing beneath the lever F, is a hook E, which is provided at its inner or pivot end with a segment E². This is also provided 65 with two projections e' and e², so placed as to engage the lower end of the lever F when the hook E is swung to its limit in either direction. This hook E swings through a slot A' in the casing and when in its upper position 70 forces the lower end of the lever F back by engagement therewith of the lug or projection e'. This holds the upper end of the lever between the pins b' upon the crank-disk, and thus prevents its rotation. When the 75 hook E is thrown down to the horizontal position, as is shown in Fig. 4, the lug or projection e² engages the opposite side of the lever F and throws its upper end out of engagement with the pins b'. The segment E² 80 upon this hook is also provided with a notch e, adapted to receive one end of a locking-lever H. The other end of this lever H projects into a slot g, formed in one side of the coin-chute G. The end of this lever is so 85 placed that the coin which passes down through the chute cannot pass the lever without forcing this end downward, and thus elevating the opposite end sufficiently to free it from the slot e. Normally the hook E is in 90 the elevated position shown by full lines in Fig. 5, and consequently the pump-operating mechanism is locked, so that the pump cannot be operated. When a coin is inserted in the chute, it will engage the lever H and free 95 the hook E, so that it may be thrown down into engagement with the upper side of the wheel-rim, as shown in the drawings.

To properly locate the wheel, a notched plate a² is provided, adapted to receive the 100 lower side of the wheel, and a hook a' is secured to the frame where it will engage the upper portion of the wheel, and thus hold it steadily. When the bicycle has been placed

in this position, the tire-nipple may be connected with the pump through the hose d , which is permanently connected to the pump-outlet.

5. The under surface of the hook E is engaged by a flat spring I , which prevents its dropping down unless engaged by the hand. The shaft E' , upon which the hook E is mounted, extends outside the casing and has a handle E'' secured thereto, by means of which it may be operated.

The operation of my device is as follows: The bicycle-wheel K is placed in the hooks a' and a'' provided therefor. The coin is then 15 placed in the coin-chute. This releases the locking-hook E and enables it to be thrown downward, so as to engage and hold the wheel. When it reaches its lowest position, the crank-disk is released and the pump may be operated. 20 When the hook E is thrown upward, it forces the lever F into engagement with the pins on the crank-disk and locks it against rotation, at the same time causing one end of the lever H to drop into the notch e , and thus 25 to lock the hook E in its upper position. To release it, the insertion of a second coin is required.

Having thus fully described my invention, I claim as new and desire to secure by Letters 30 Patent—

1. A coin-controlled bicycle-pump, comprising a casing, a pump and its operating mechanism within the casing, said mechanism including a rotating disk having a series of projections thereon, a power-crank external the casing and connected with the pump-operating mechanism, a locking-lever adapted to normally lie between adjacent projections on the disk to lock it, and coin-controlled means 35 for releasing the lever from the disk, substantially as described.

2. The combination of a pump and operating means therefor, including a rotating disk having a series of projections to prevent operation of the pump, a movable hook adapted 45 to engage and hold the bicycle and also to engage the locking-lever to shift it, and a coin-controlled lever normally having locking engagement with the hook and released therefrom by the insertion of a coin, substantially as described.

3. A coin-controlled bicycle-pump, comprising a pump, a crank-shaft, a crank-disk on the shaft having a series of locking projections, connections from the disk to the pump- 55

piston, a locking-lever normally engaging the projections on the disk, a hook adapted to engage and lock the bicycle-wheel, means by which said hook may control the crank-disk-locking lever, a locking-lever engaging said hook, and a coin-chute directing the coin upon said lever and thereby releasing the hook, substantially as described.

4. A coin-controlled bicycle-pump, comprising a pumping mechanism, a lock therefor, a hook adapted to engage and hold the wheel and having controlling connection with the pump-locking mechanism, said hook having a notched segment attached, a catch adapted to drop into the notch in said segment, and a coin-chute having one end of the catch projecting into it, whereby the catch is engaged by a coin and freed from the hook, substantially as described.

5. A coin-controlled bicycle-pump, comprising a pump, a crank-shaft having a disk thereon provided with locking projections, and operative connections with the pump, a pivoted hook adapted to engage the bicycle-wheel and having a locking-notch, a pivoted catch normally engaging said notch, a coin-chute having a slot receiving one end of the catch, whereby the coin may engage the catch and free it from the hook, and a pivoted lever engaging by one end the projections on the 85 crank-disk and engaged at its other end by the hook, substantially as described.

6. The combination of a pump and operating means therefor, with a locking-lever normally engaging and locking the operating 90 means, a movable hook adapted to engage and hold the bicycle and also to engage the locking-lever to shift it, and a coin-controlled lever normally having locking engagement with the hook and released therefrom by the 95 insertion of a coin, substantially as described.

7. The combination of a pump and operating means therefor, a lock engaging said operating means to prevent their use, a movable hook adapted to engage and hold the bicycle-wheel and also to control the lock for the pump-operating mechanism, and a coin-controlled locking-lever engaging said hook and adapted to be released by the insertion of a coin, substantially as described.
